In Germany November 28, 1932

3 Claims. (Cl. 101—154)

This invention relates to an improved method and apparatus for offset printing, and is especially adapted for the printing of imitation wood grains, and the like.

5 Machines for effecting wood grain finishes and the simulation of other natural surfaces on hard surfaces usually embody some form of a master plate or roll having a variegated indented surface, to which pigment is applied in a suitable 10 manner, and thereafter the surplus pigment on the roll surface is scraped or removed therefrom, and a rubber or gum offset roll is brought into contact with the pattern or pigment carrying roll to effect a transfer of the pigment from the interstices to the surface to be grained.

Indented or master or pattern rolls or plates have been made in various ways and it is the present practice to reproduce on the plate or roll surface an etched pattern of the grain or design by 20 the well-known photogravure process. To obtain continuous productive results at comparatively high press speeds when using such an etching roll, the transfer of the pigment from the pattern roll to the offset roll and the action of such pigment 25 while on the offset roll between the point of application thereto and the point of application to the surface to be grained, become highly important.

It has been found, from past experience with 30 offset printing mechanisms, that when the pattern or master roll came in contact with the offset roll, the colors which were transferred to the offset roll from the pattern roll were torn apart. It has also been found that due to the rate of 35 speed at which the presses were operated, and other operating conditions, the colors did not level out on the offset roll before they were applied to the work surface to be decorated. This disadvantage has been apparent in all offset 40 printing presses, even where the presses were used to print the reproductions of type, illustrations and the like on paper. However, when there is a demand for absolute sharpness of outlines and 45 for tone values true to the natural object being simulated, such as is demanded for the successful simulating of wood grains, marbles and tiles, the disadvantage above set out becomes more pronounced. Likewise, this disadvantage is more objectionable when surfaces, other than paper, are 50 being printed, such as, for instance, wood, metal, stone or glass.

The general object of this invention is the provision of a method and apparatus, the use of 55 which will cause the pigment or color to level and

smooth out on the transfer roll, despite the comparatively high speed of operation on the press.

A more specific object is to provide a method and apparatus for treating the pigment or colors while they are on the transfer or offset roll, so as to result in a clearer and sharper reproduction which will more truly simulate the object being reproduced and at the same time prevent excessive drying of the color remaining on the offset roll after the impression has been made. 10

Other objects of my improved method and apparatus will become more apparent from the following description, reference being had to the accompanying drawing, and the essential features of the invention will be set forth in the 15 claims.

In the drawing, Fig. 1 is a vertical section through an offset printing and/or graining machine, constructed to carry out my improved method; Fig. 2 is a vertical section, as indicated 20 by the line 2—2 on Fig. 1.

In the drawing, I have indicated more or less diagrammatically an offset printing press, which includes a pattern roll 10. The pattern roll is provided with a grained metallic covering 11, the pattern of which may be effected in any suitable manner but preferably by the well-known photogravure process, wherein a screen is used when the carbon resist is made, preparatory to the actual etching of the roll, thus forming a screen 30 intaglio printing process. An offset roll 15 is provided, and mounted in frictional rolling contact with the graining roll 10. At least one of the rolls is driven, as, for instance, by a suitable motor, not shown, but which is drivingly connected to one of the rolls 10 or 11. 35

The offset or transfer roll 15 is provided with a blanket or covering 17, which may comprise rubber composition, gum, or a glycerine and glue compound, such offset rolls being well known at 40 the present time.

Below the offset roll 15 is a work-supporting roll 20, which, as shown in Fig. 1, maintains the upper surface of the work W in contact with the periphery of the offset or transfer roll 15, so that 45 the pigments or colors will be transferred from the roll 15 to the upper surface of the work.

The pigments or colors are applied to the pattern roll by a fountain roll 25, which contacts with the pattern roll, as shown in Fig. 1, and which rotates with its lower region in a pigment-carrying fountain trough 26. Pigment or color is supplied to the fountain trough 26 in any suitable manner, such as, for instance, manually by the operator. Disposed above the fountain 55

trough 26 is a reciprocating doctor blade 30. This doctor blade bears against the surface of the grained or etched pattern roll 10 and removes all surplus pigment deposited thereon by the 5 fountain roll 25.

A suitable scraper 18 is provided to eliminate from the offset roll any pigment remaining thereon after the transfer to the work W has been effected. A tray 19 is provided to receive such 10 pigment or color material as it is removed from the transfer roll 15 by the scraper blade 18.

The mechanism above described is representative of present-day offset printing presses and graining machines, and my improved method and 15 apparatus is readily adapted to be incorporated in such mechanism.

My improved method comprises heating the exposed surface of colors and pigments, while on the offset roll prior to the transfer of such color 20 to the work and at the same time applying substantially no heat to the color remaining on the roll after such transfer has been made, and by so doing transform such colors or pigments to a more liquid state, thereby permitting the colors 25 to promptly level and smooth out on the transfer roll, and at the same time eliminating the drying out of the minute film of ink remaining on the transfer roll after the impression has been made, enabling the removal of this color in the 30 usual manner, and allowing the printing or graining operation to be carried out at a comparatively high rate of speed.

In the past, colors on the rolls of printing couples have been heated by heating the surface 35 of the rolls, generally by the application of heat internally to the rolls. Such heating of the rolls causes the entire surface of the rolls to become heated, resulting in the drying on the roll of the thin film of pigment remaining thereon after 40 the impression has been made. The drying of this thin film of pigment prevents its removal from the roll and more than counter-balances the benefits derived from the heating of the rolls, by building upon the offset roll of an increasing 45 thickness or film of dried color and detracting from the sharpness of design obtainable.

My improved method and apparatus is also especially advantageous when used in connection with presses having offset rolls made of a 50 composition which is affected by heat. Rolls of this type are used to a great extent to obtain the accurate results demanded in the simulating of wood grains and the like, as such rolls receive for all practical purposes all the color from the 55 pattern roll and transfer it to the work being decorated. It has been found disadvantageous to heat such rolls internally, as such application of heat softens the rolls and to a certain extent destroys their accuracy.

60 In the drawing I illustrate an apparatus for heating the external surface of the roll 15. While, as above set out, this method of heating the roll 15 is especially advantageous when certain types of composition offset rolls are used, it is 65 nevertheless adaptable to all types of rolls and presents an advantageous method of heating the colors in existing presses wherein the construction of the offset rolls, or of the machines themselves either prevent or make the internal heating 70 of the offset rolls difficult.

As shown in Fig. 1, I accomplish the warming of the colors on the offset roll 15 by directing a blast of warmed air toward the surface of the color on the roll between the point of application of the ink to the roll and the point

of transfer of the ink to the work. Warmed air is drawn through a suitable conduit 60 by a fan 61 and forced through a conduit 62 into a nozzle 63 having an elongated discharge opening 64 which directs the warmed air toward 5 color on the surface of the roll 15, thereby warming the colors. The amount of heat applied to the colors on the roll is adjusted by regulating the temperature of the heated air and by adjusting the speed of the motor 65, 10 which propels the fan 61, thereby regulating the volume of heated air applied to the surface of the roll.

I find it desirable to prevent the heat from affecting the colors while they are in the ink 15 fountain or on the pattern roll, as this would change the consistency of the ink itself, which consistency is maintained at a predetermined point commensurate with the nature of color being used and the speed of the press. As shown 20 in Fig. 1, I provide a guard 70 to shield the pattern roll and ink fountain from the blast of heated air. Such guard is preferably made of a heat insulating material.

From the foregoing description it will be seen 25 that the heated air is, due to the location of the nozzle 53, directed to only that portion of the roll which has received color from the pattern roll and has not given up its color to the work. The amount of color on this portion of the roll 30 has sufficient body to permit regulation of the amount of heat to prevent drying of the ink. Even this amount of heat would be sufficient to dry out the color remaining on the offset roll after the transfer to the work has been effected. 35 However, by my arrangement the heat is restricted to the area of the roll having a comparatively heavy coating of color. Hence, any disadvantageous drying of the color is eliminated.

40 While I have illustrated my invention in connection with a rotary printing machine, it is apparent that it is equally well adapted for use in flat bed printing or graining presses. My invention likewise is not confined to single color 45 printing, but is equally as advantageous when used in connection with multicolor presses. In such instances each offset roll is heated.

I claim:—

1. An apparatus for decorating surfaces, 50 comprising a frame, a roll mounted in the frame, a pattern on said roll, means to supply a color to said roll, means to remove excess color from said roll, an offset roll rotatably mounted in said frame and in contact with such pattern roll 55 to receive the color therefrom, means to support articles to be decorated in contact with said transfer roll whereby color is transferred to such articles, means to heat the color after it has been transferred to said offset roll and before 60 it has been transferred to the article to be decorated, said last-named means including means to force a current of heated air toward substantially all of the color on said offset roll and simultaneously toward the work to be decorated, 65 and means to shield the pattern roll from such heated current of air.

2. The method of decorating surfaces comprising the transferring of color from a pattern to an offset printing roll, thereafter transferring 70 such color to the work to be decorated, removing the color remaining on the roll after the transfer to the work has been effected, and including applying heat to the color on the offset roll between the point of application thereto 75

and the point of transfer of such color to the work without applying heat to the color remaining on the roll between the point of transfer and the point of removal of such color.

3. An apparatus for decorating surfaces comprising a frame, an offset printing roll mounted in said frame, means to apply color to said roll, means to support articles to be decorated in contact with said transfer roll whereby color is transferred from the offset roll to such articles,

means to remove from said roll the color remaining thereon after the transfer to the work has been effected, and means to heat the color on the roll between the point of application thereto and the point of contact with the work 5 without applying heat to the color on the roll while it is between the point of contact with the work and the color removing means.
